[57] **CLAIM**

The ornamental design for a deodorizer bar, as shown and
described.

DESCRIPTION

FIG. 1 is a perspective view of a deodorizer bar showing my
new design;

FIG. 2 is a top plan view of the deodorizer bar shown in FIG.
1;

FIG. 3 is a bottom plan view of the deodorizer bar shown in
FIG. 1;

FIG. 4 is a right side elevational view of the deodorizer bar
shown in FIG. 1;

FIG. 5 is a left side elevational view of the deodorizer bar
shown in FIG. 1;

FIG. 6 is a front elevational view of the deodorizer bar
shown in FIG. 1; and,

FIG. 7 is a rear elevational view of the deodorizer bar
shown in FIG. 1.

The broken-line showing of environmental structure is for
illustrative purposes only and forms no parts of the claimed
design.
